DESIGN FOR A CORRESPONDENCE SERVICE BOOK

Joseph Giordano, Philadelphia, Pa.

Application January 18, 1934, Serial No. 50,435

Term of patent 7 years

To all whom it may concern:

Be it known that I, JOSEPH GIORDANO, a citizen of the United States, residing at 1503 So. Juniper Street, in the county of Philadelphia and State of Pennsylvania, have invented a new, original, and ornamental Design for a Correspondence Service Book, of which the following is a specification, reference being had to the accompanying drawing, forming part thereof.

Fig. 1 is a perspective view of a correspondence service book, with the top cover slightly raised, showing my new design; and

Figure 2 is a plan view of one of the leaves from the book.

I claim:

The ornamental design for a correspondence service book, as shown and described.

JOSEPH GIORDANO.
